CHARLES FREDERICK GREEN, OF HORNCHURCH, ENGLAND, ASSIGNOR TO A. B. DICK COMPANY, OF CHICAGO, ILLINOIS, A CORPORATION OF ILLINOIS.

DUPLICATING-MACHINE.

1,139,117.

Specification of Letters Patent.

Patented May 11, 1915.

Application filed May 26, 1914. Serial No. 840,985.

To all whom it may concern:

Be it known that I, CHARLES FREDERICK GREEN, a subject of the King of Great Britain, residing at Northfield, Herbert Road, 5 Hornchurch, Essex, England, have invented certain new and useful Improvements in Duplicating-Machines, of which the following is a specification.

My invention relates to rotary duplicating machines, and it refers particularly to duplicators of the type in which a closed cylinder is employed for the stencil and within which the inking mechanism is disposed.

15 The object of my invention is to provide means whereby ink may more readily and conveniently be introduced into the reservoir in the interior of the cylinder and whereby a closure is provided for the ink 20 reservoir which is adapted to be opened by the device which is used for filling the reservoir.

In duplicating machines of this type, it has been customary, in order to introduce 25 the ink into the reservoir, to provide an opening in one of the end walls of the cylinder, which opening has been provided with a door or covering in order to prevent evaporation of the ink, and to prevent dust getting 30 into the reservoir. One disadvantage of this construction has been that the removal and replacement of this cover is very apt to ink the fingers.

By my present invention, I provide a collapsible container or tube of such dimensions 35 as to hold a charge of ink sufficient to fill the reservoir to the desired extent. The nozzle of the collapsible tube is adapted to be inserted through a suitable orifice in the 40 end wall of the cylinder, this orifice being provided at its inner end with a spring controlled cover. The nozzle of the container is so shaped that it may engage the cover or some part operatively connected therewith 45 to serve as a means for operating the cover to open the passage for the ink to the reservoir, the cover returning to its closing position when the tube is removed from the opening. By this means the necessity for 50 providing a special instrument for operating the cover is obviated and at the same time, the danger of soiling the hands is removed.

In order that a clearer understanding of 55 my invention may be had, attention is here-

by directed to the accompanying drawings forming part of this specification and illustrating the preferred form of my invention.

In the drawings, Figure 1 represents an end view of a drum of a rotary duplicator 60 to which the invention has been applied, Fig. 2 is a vertical section on line 2—2 of Fig. 1 looking in the direction of the arrow, Fig. 3 is a sectional view taken on line 3—3 of Fig. 1, Fig. 4 is a side view of the end 65 of a collapsible ink container, about to be inserted into the ink filling orifice of the drum, Fig. 5 is an end view of the ink tube, Fig. 6 is a section through the neck of the tube on line 6—6 of Fig. 4 and Fig. 7 is a 70 view similar to Fig. 1, with the closure for the ink filling orifice in open position.

Referring to the drawings, the reference character 1 represents an end wall of the cylinder of the machine, in which is revolvably mounted a bushing or sleeve 2 which is provided with pins 3. Seured to the inner end of the bushing 2 is an arm 4 provided at its outer end with a pin 5 which is adapted to contact the upper surface of one arm 80 of a bell-crank lever 6. Lever 6 is pivoted at 7, and spring 8, which is secured at one end to the inner face of the end plate 1 of the drum, by any suitable means, such as the screw 9, has its other end secured at 10 85 to the lower end of the depending arm of the bell-crank. The effect of the spring is to always keep the upper arm of bell-crank 6 in contact with pin 5 on arm 4, the upper arm of bell-crank 6 forming a closure 90 for the inner end of the bushing 2.

In order to make the closure tight so as to prevent as far as possible the entry of dust or dirt, a housing 11 is provided for the free end of lever 6 when in its closing position. 95 The plate 11 is under cut upon its under side, and provided with a wedge shaped packing piece 12 indicated in Fig. 2. The free end of lever 6 is similarly tapered so that the upper arm of bell-crank 6 is held 100 closely over the end of the ink filling orifice when the lever is in its closed position with its end underneath housing 11 as stated.

The tube or container for the ink is shown at 13 in Fig. 4, the tube being provided with 105 a nozzle or nose 14, which latter is provided upon opposite sides with longitudinal grooves 15, which are adapted to engage pins 3 of the revoluble bushing when the device is to be operated. Grooves 15 are 110

bent at a point intermediate their ends, so that the inner portions of the grooves are out of alinement with the outer portion of the grooves, preferably in the manner indicated in Fig. 4 of the drawings. When the ink reservoir is to be filled, the end 14 of the container is first introduced into the bushing 2 with the ends of slots 15 engaging pins 3. The container 13, now being turned through a small angle, rotates bushing 2 and causes pin 5 on arm 4 secured to the bushing to depress the upper arm of bell-crank 6 into the position shown in Fig. 7, so that the lever 6 no longer obstructs the opening through the bushing. A further partial rotation is now given the ink container 13 causing pins 3 to enter the rear portions of grooves 15, whereupon the container is advanced so that its end projects into the interior of the drum when the ink may be discharged by compressing the container. Thereupon, the container may be withdrawn by turning the same sufficiently to free the pins 3 from the slots 15, whereupon the container may be removed and the upper arm of bell-crank 6 will return to its closing position over the end of the orifice under the influence of spring 8.

The container may, if desired, be provided with the usual screw cap or any other form of removable closure. I also may, if it be deemed desirable in some instances, provide the container with a sealed end or nozzle, and mount a knife blade or other suitable puncturing instrument within the cylinder in such a manner that the nozzle of the container is perforated when it is inserted and so permits the discharge of the ink.

While I have described and illustrated in detail one embodiment of the invention, it should be understood that the invention is not strictly limited thereto, as the construction and arrangement of the parts may be considerably varied within the scope of my invention as is indicated by the appended claims.

Having now particularly described my invention, what I claim and desire to protect by Letters Patent is as follows:—

50 1. In a rotary duplicator, the combination of a member having an orifice therein, a revoluble member mounted in said orifice, a closure mounted on the inner side of said first member and normally covering said orifice, and means for moving said closure from closing position upon the revolution of said revoluble member, said revoluble member being adapted to be engaged from the outer side of said first member for the 60 rotation thereof, substantially as set forth.

2. In a rotary duplicator, the combination of an end plate for a closed cylinder, having an orifice therein, a closure mounted on the inner side of said plate and normally covering said orifice, a pivoted arm adapted to

force said closure away from closing position, and means within said orifice adapted to be engaged by an inserted instrument for moving said arm to move said closure, substantially as set forth. 70

3. In a rotary duplicator, the combination of an end plate for a closed cylinder, having an orifice therein, a closure mounted on the inner side of said plate and normally covering said orifice, a pivoted arm adapted to 75 force said closure away from closing position, and a sleeve mounted in said orifice, connected to said arm to oscillate the same by its rotation, substantially as set forth.

4. In a rotary duplicator, the combination 80 of an end plate for a closed cylinder, having an orifice therein, a closure mounted on the inner side of said plate and normally covering said orifice, a pivoted arm adapted to force said closure away from closing position, and a sleeve mounted in said orifice, connected to said arm to oscillate the same by its rotation, said sleeve being constructed to interlock with the nozzle of a collapsible ink container, when the latter is inserted 85 within said orifice and into engagement with said sleeve, substantially as set forth. 90

5. In a rotary duplicator, the combination 95 of an end plate for a closed cylinder, having an orifice therein, a spring-pressed closure on the inner side of said plate normally covering said orifice, a sleeve revolubly mounted in said orifice and having engageable means therein, and an arm secured to said sleeve and having means thereon for 100 moving said closure against its spring-pressure, substantially as set forth.

6. In a rotary duplicator, the combination 105 of an end plate for a closed cylinder, having an orifice therein, a spring-pressed closure on the inner side of said plate normally covering said orifice, means engaging said closure when in closing position to cause it to seat closely over said orifice, a pivoted arm adapted to force said closure away from 110 closing position, and engageable means within said orifice connected to said arm for operating the same, substantially as set forth.

7. In a rotary duplicator, the combination 115 of an end plate for a closed cylinder, having an orifice therein, a spring-pressed closure on the inner side of said plate normally covering said orifice, a sleeve revolubly mounted in said orifice and having pins thereon, an arm secured to said sleeve adapted to move 120 said closure against its spring pressure, said pins being adapted for engagement with slots in the nozzle of a collapsible ink container, which nozzle is adapted to enter said orifice, substantially as set forth. 125

8. In a rotary duplicator, the combination 130 of an end plate for a closed cylinder, having an orifice therein, a closure mounted on the inner side of said plate and normally covering said orifice, and means adapted to 135

coact with the nozzle of a collapsible ink container adapted to enter said orifice to remove said closure from closing position upon actuation of the container, said means and nozzle being so constructed that a partial rotation of said nozzle within said orifice serves to move said closure, and a further rotation of said nozzle is required to

permit the entry of said nozzle within the cylinder, substantially as set forth. 10

This specification signed and witnessed this 14th day of May, 1914.

CHARLES FREDERICK GREEN.
